Primary Examiner — Susan Bennet Hattan*Assistant Examiner* — Marie D. Fast Horse(74) *Attorney, Agent, or Firm* — Lee & Hayes, PLLC(57) **CLAIM**

The ornamental design for an electronic device, as shown and described.

DESCRIPTION

FIG. 1 is a first perspective view of an electronic device, taken from the front.

FIG. 2 is a second perspective view of the electronic device, taken from the back.

FIG. 3 is a front view of the electronic device of FIG. 1.

FIG. 4 is a back view of the electronic device of FIG. 1.

FIG. 5 is a left-side view of the electronic device of FIG. 1.

FIG. 6 is a right-side view of the electronic device of FIG. 1.

FIG. 7 is a top view of the electronic device of FIG. 1; and, FIG. 8 is a bottom view of the electronic device of FIG. 1. The broken lines represent features of the electronic device which form no part of the claimed design.
